[57] CLAIM

The ornamental design for a urine screening card for
use with an automated microbial identification ma-
chine, substantially as shown.

DESCRIPTION

FIG. 1 is a top plan view of a urine screening card
embodying the new design;

FIG. 2 is a right side view of the card of FIG. 1;

FIG. 3 is a lower side view of the card of FIG. 1;

FIG. 4 is a bottom plan view of the card of FIG. 1
rotated right side over left;

FIG. 5 is a side view of the card of FIG. 4 looking into
the top thereof as oriented in FIG. 4; and

FIG. 6 is the right side view of FIG. 4.

FIG. 1FIG. 2FIG. 3FIG. 5FIG. 4FIG. 6
